ATTORNEYS

UNITED STATES PATENT OFFICE.

MICHAEL V. GEARON, OF CHICAGO, ILLINOIS.

METAL CROSSTIE.

Application filed October 26, 1925. Serial No. 64,878.

My invention relates to improvements in metal railroad ties, and it consists in the combinations, constructions, and arrangements herein described and claimed.

5 An object of my invention is to provide a metal cross tie for railroads which has great strength and resiliency.

A further object of my invention is to provide a metal cross tie which can be 10 readily made by automatic machinery, thus rendering the device economical to manufacture.

A further object of my invention is to provide a metal tie having special reinforcing 15 means for that portion of the tie just underneath the rails.

Other objects and advantages will appear 20 in the following specification, and the novel features of the invention will be particularly pointed out in the appended claims.

My invention is illustrated in the accompanying drawings, forming part of this application, in which

25 Figure 1 shows a development of the blank from which the tie is made,

Figure 2 is a side view of a portion of a complete tie, the rails and a portion of the tie being shown in section,

30 Figure 3 is a perspective view showing one of the reinforcing members,

Figure 4 is an enlarged sectional view of a portion of the tie, and

Figure 5 is a similar section at another point.

35 In carrying out my invention I make use of a single piece of sheet metal, preferably sheet steel. Figure 1 shows the piece in its entirety. It will be observed that there are eight plane sections at one end, these sections being indicated at 1 to 8 inclusive.

40 The sections are designed to be bent along the dotted lines, such as those shown at 1^a, 2^a, 3^a, etc. Sections 9, 10 and 11 are provided with corrugated portions, or portions 45 stamped with a depression on one side and a corresponding ridge on the other. Thus, in the section 9, the depressions are shown at 9^x. At 9^y, in the same section, are shown oblong ridges between the depressions. The 50 section 12 has a smooth surface, with the exception of the oblong ridges 12^y. The next three sections, 13, 14 and 15, respectively, are similar to the sections 9, 10 and 11 in that they have depressions, such as

those shown at 13^x and oblong ridges, such 55 as those shown at 13^y, while the last section 16 is similar to the section 12.

In forming the tie, the sections are bent along the dotted lines and are wrapped around in spiral form. Thus the first section 1, as viewed in Figure 1, would be bent 60 on the line 1^a toward the rear of the plane of the paper. This would preferably be accomplished by placing it on a mandrel so as to wrap the sections one upon another. 65 The first two layers consisting of the eight sections would be plain. The next four sections would give a section on each side, i. e., the sections 9 and 11, one on the bottom, section 10, while section 12 would come on 70 the top, and further winding would bring section 13 into registration with section 9, section 14 into registration with section 10, 15 with 11, and 16 with 12. The corrugations or depressions, as stated, would have 75 ridges on the opposite sides of the sections, and these are so arranged as to cause the convex portions to enter the concave portions of the overlapping sections so as to cause the sections to be nested in the manner 80 shown in Figures 4 and 5. In Figure 4, it will be seen that the ridges 15^y register with the ridges 11^y of the section 11, while the depressions 15^x register with the depressions 11^x. In Figure 5, it will be seen that 85 the ridges 16^y and 12^y are nested. All of the sections 13, 14, 15 and 16 have extended flanges 13^a, 14^a, 15^a and 16^a at each end. These flanges are turned under, as shown in Figure 4, and are held to the coiled sections 90 by rivets 17.

The coiled sections are spot-welded together, thus rendering the tie virtually a unitary structure having great strength in proportion to its weight.

95 In order to reinforce the tie at the portion thereof underneath the rails, I provide a sheet metal coil 18, such as that shown in Figure 3. This is a single strip of metal having the convolutions spaced 100 apart. The sides of the coils are provided with bolt or rivet openings 18^x to receive rivets 19 which pass through the body portion of the tie so as to hold the member 18 in position underneath the rail, see Figure 2.

The rails 20 are held to the tie preferably by means of bolts 21 which pass

through the top portion of the tie, the lower portions of the bolts being within the space surrounded by the coiled reinforcing member 18.

From the foregoing description of the various parts of the device, the operation thereof may be readily understood. The metal tie is very strong in comparison with its weight. The sides being corrugated tend to add to the rigidity of the tie so as to prevent sagging or bulging due to the weight of the load on the rails. The reinforcing member 18 is so placed that the thrust is along the walls of the reinforcing member, thus adding to the rigidity of the device. The nesting of the corrugated portions, including the ridges and depressions, makes the coils compact and at the same time gives them the necessary strength to carry out the purpose intended. When the flange portions 13^a, 14^a, etc., are turned under, they firmly bind all of the sections together.

A metal tie, such as that described, may be made to fit any rail or rail fastening, since holes can be bored in the walls of the tie at any point, and bolts or other suitable fastening devices may be passed therethrough, as shown at 21 in Figure 2.

I am aware that metal ties made of sheet coiled metal portions have been used before. Such construction appears in the patent to J. Gearon Sr., 963,542 of July 5, 1910. In this patent, however, it was necessary to reinforce the tie with ballast filling within the interior of the tie. The present tie, however, is an improvement in that it requires no ballast filling due to the corrugated form of the tie itself and the reinforcement.

It being plainly apparent that a variety of corrugations and depressions of different patterns can be stamped or fabricated in sheets of metal and the said sheets used to form a tie by wrapping, registering, nesting and welding such. Such sheets together on a tie forming mandrel and folding, lapping and riveting them in such form, I wish to have it known that this invention covers the use of any pattern of depression or corrugation that may be found advantageous to use in its construction either before

or after the sheet is thus wrapped, folded and lapped into the form of a tie.

I claim:

1. A metal cross tie constructed of a single piece of sheet metal having sections coiled to form a plurality of layers, the layers of certain sections having corrugations adapted to nest within similar corrugations of adjacent sections, and means for binding the overlapping sections together.

2. A metal cross tie comprising a single sheet of metal folded into a plurality of sections to form a hollow structure having a plurality of layers, certain of the sections having corrugations arranged to nest with the corrugations of adjacent overlapping sections, and flanges carried by the outer sections and being bent over the ends of the inner sections, and means for securing the bent-over flanges to the inner sections.

3. A railroad cross tie comprising a single sheet of metal having sections folded over one another, said sections being welded together to form a hollow body portion and certain sections having nested corrugations, and reinforcing members disposed within the interior of the tie, said reinforcing members comprising coiled metal sheets secured to the walls of the tie, certain of the walls of the reinforcing sheets being disposed transversely with respect to the layers forming the tie body portion, whereby the weight of the load is transmitted through the planes of the transversely disposed walls.

4. A railroad cross tie comprising sheets of metal having a plurality of sections folded together to form a hollow body portion, means for securing said folded sections together, reinforcing members disposed within the tie underneath the rail-bearing area, said reinforcing members consisting of a single sheet of metal arranged in rectangular-shaped coils, certain walls of said rectangular-shaped coils being disposed transversely with respect to the walls of the main body portion, and rail securing members passing through the rails and having their lower portions disposed within the innermost convolution of said reinforcing member.

MICHAEL V. GEARON.
